UNITED STATES PATENT OFFICE

JOHN M. CLARK, OF DETROIT, MICHIGAN, ASSIGNOR TO UNIVERSAL BUTTON FASTENING & BUTTON COMPANY, OF DETROIT, MICHIGAN, A CORPORATION OF MICHIGAN

BUTTON

Application filed August 3, 1931. Serial No. 554,732.

This invention relates to metal buttons, and among other objects aims to provide a durable button which may be made cheaply and by a few, simple operations.

5 The nature of the invention may be readily understood by reference to one illustrative construction embodying the invention and shown in the accompanying drawing.

In said drawing:

10 Fig. 1 is a sectional elevation of a button on an enlarged scale;

Fig. 2 is a bottom plan view of the button taken from the plane 2—2 of Fig. 1;

15 Fig. 3 is a top plan view of the button, on a scale smaller than that of Fig. 3, and showing the decorative embossing on the button top;

20 Fig. 4 is a side elevation of a button similar to that shown in Figs. 1, 2, and 3 but designed for attachment by a single prong fastener; and

Fig. 5 is a bottom plan view of the button shown in Fig. 4.

25 The various elements of the illustrative button are made of raw materials of such form as to require a minimum fabrication or treatment to connect them into button parts. The shank 10 of the button being generally cylindrical in character and embodying a recess 11 for upsetting a fastener prong, is made of solid, cylindrical rod stock whose diameter is that of the shank of the finished button. The rod stock may be of any appropriate material and can advantageously be soft steel which may be readily formed and yet is sufficiently hard so that the inner surface of the die cup 11 will turn or upset the fastener prongs. The head 12 of the button being flat in character is made from flat 30 or sheet stock such as sheet steel whose thickness is approximately that of the button head and which requires merely punching to proper shape to form the button head.

35 In fabricating the button, sections or blanks may be cut from the rod stock of a length approximately that of the total length of the button shank. The button head 12 is preferably punched from ribbon stock of a width slightly in excess of the diameter of the head, which is generally circular. At

some stage during the fabrication and assembly of the button parts the die recess 11 is formed in one end of the button shank by an appropriate operation. This may be effected by an appropriate operation such as 55 drilling with a drill whose end has the contour of that of the die recess or formation by a pair of dies.

If the button be designed for attachment by a double prong fastener, the end of the button shank is provided with an element extending transversely of the recess 11 and about which the prongs 13 of the fastener 14 may be bent from opposite sides. The element in this case comprises a short section of 60 strong spring wire 15 seated on a shoulder 16 just inside the die recess 11 and is held therein by crimping or upsetting, as at 17, portions of the rim of the recess over upon the ends of the wire 15. The distance between the wire 15 and the bottom of the recess 11 is such that, upon attachment of the button, the prongs of the fastener will be forced against the curved sides of the recess 11 and will be 65 curled thereby tightly around the bar 15. Preferably pressure is exerted against the button head and fastener head during the attaching operation so that fabric 18 to which the button is attached is tightly compressed between the fastener head and the base of 70 the button which is held in such compressed condition by the firm bending of the fastener prongs about the bar. 75

80 For single prong attachment (see Figs. 4 and 5) the margins of the die cup 19 are contracted appropriately to form a restricted opening 20 to receive the fastener prong 21. In the present case the restricted opening 20 is provided by bending inwardly the margins 22 of the die recess after the formation of the recess either by the drilling or die operation mentioned above in connection with the die recess 11. The diameter of the restricted opening 20 is preferably less than that of the fastener prong so that the fastener prong must be forced into the opening and is therefore gripped tightly by the margins of the opening 20. The curved surface of the die recess 11 serves to upset the fastener prong 21 and enlarge it just inside the opening, 100

so that the fabric to which the button is attached is tightly gripped between the fastener head and the base of the button.

The button head 12 may be attached to the button shank in any appropriate manner, such as by spot welding or, as here shown, riveting the end of the button shank over the button head. For the latter mode of assembly, the button head is perforated centrally at 23 to receive the button shank. At some stage of the fabrication of the button after the assembly of the button head and button shank, a blow is delivered to the end of the shank such as to rivet it over, as at 24, upon the face of the button. In such operation, the shank is left free to expand slightly as at 25, underneath the head, so that the latter may be firmly gripped on both sides and will be immovably attached to the shank. In Fig. 1 the riveted and upset portions 24 and 25 of the shank are somewhat exaggerated for the sake of better illustration.

The button head is preferably provided with a protective and decorative covering which serves also to conceal or obliterate any evidence of the riveting or other mode of attaching the button head to the shank. In the present case the covering shown in the form of a thin metal shell 26 is attached to the button head by crimping its margins 27 underneath the head. The shell 26 is preferably non-corrosive in character and may be provided with any desired form of embossing 28 either for the purpose of decoration or to exhibit a trademark or both.

Obviously the invention is not limited to the details of the illustrated embodiment herein disclosed, since these may be variously modified. Moreover, it is not indispensable that all features of the invention be used conjointly since various features may be advantageously employed in different combinations and sub-combinations.

Having described my invention, I claim:

A button of the character described comprising in combination a solid, soft steel, rod-like button shank of substantially uniform diameter throughout, a flat sheet metal head having a central perforation into which said shank projects, said shank being upset on opposite sides of said head to secure the latter to said shank, the opposite end of said shank being formed with a concave recess for upsetting a pronged attaching fastener and having a member for engaging the upset fastener to prevent its withdrawal from said recess, and a decorative metal shell covering the top of said head and having margins crimped underneath said head.

In witness of the foregoing I affix my signature.

JOHN M. CLARK.
